UNITED STATES PATENT OFFICE.

WILLIAM E. SMITH, OF MILLTOWN, NEW JERSEY, ASSIGNOR TO THE INTERWOVEN MILLS, INC., OF NEW BRUNSWICK, NEW JERSEY, A CORPORATION OF NEW JERSEY.

SEAMLESS TUBULAR KNIT FABRIC AND PROCESS OF KNITTING THE SAME.

1,390,827.

Specification of Letters Patent. Patented Sept. 13, 1921.

Application filed May 5, 1919. Serial No. 294,784.

To all whom it may concern:

Be it known that I, WILLIAM E. SMITH, a citizen of the United States, residing at Milltown, in the county of Middlesex and State of New Jersey, have invented certain new and useful Improvements in Seamless Tubular Knit Fabrics and Processes of Knitting the Same; and I do hereby declare the following to be a full, clear, and exact 10 description of the invention, such as will enable others skilled in the art to which it appertains to make and use the same.

My invention consists in the novel features hereinafter described reference being had to the accompanying drawings which illustrate my improved process, together with two means for carrying the same into effect, selected by me for purposes of illustration, and the fabric or stocking produced 20 by my improved process, and my said invention is fully disclosed in the following description and claims.

My invention relates to the fashioning of seamless tubular fabrics, and particularly 25 to the fashioning of stockings, and is an improvement on the process and fabric set forth in Letters Patent of the United States granted to Edward E. Kilbourn, William E. Smith, and I. W. Kilbourn, No. 1,110,443, 30 dated Sept. 15, 1914, and on the process and fabric set forth in Letters Patent of the United States No. 1,231,443, dated Jan. 26, 1917, granted to William E. Smith.

The fashioning of seamless stockings or 35 of tubular knit fabric generally is surrounded by great difficulty, owing to the fact that the fabric is knit as a tube on a circular series of needles of small diameter, and the difficulty has increased of late owing to the 40 fact that the demand for fine, close knit fabrics has necessitated the increasing of the number of needles in the circular series, while the size or diameter of the cylinder itself has in many instances been reduced, 45 so that as many as 240 or more needles are arranged in a circle having a diameter of only a few inches, and must be operated for both circular and reciprocating work to produce a seamless stocking. The patent of 50 Kilbourn, Smith, Kilbourn, above mentioned, first disclosed the idea of making the sole of a stocking actually longer than the corresponding top portion of the foot (which ordinarily contains the same num-

ber of courses) to fashion the stocking to 55 the foot and prevent the formation of wrinkles on the top of the toes and instep, which otherwise will form, where the same amount of fabric is knit in the top and sole portions, and which constitutes one of 60 the chief objections to circular knit, or seamless stockings. In this patent the increase in the length of the sole was accomplished by knitting longer stitches, a filling thread being inserted to fill up the mesh and im- 65 part the necessary weight to the sole. This, however, requires the presence in the machine of special mechanism for changing the length of the stitches, and the use of extra filling yarn in the sole, and while effi- 70 cient, is expensive. In my former Patent No. 1,231,443, I disclosed a method of fashioning the sole of a stocking (or tubular knit fabric generally) by knitting a plurality of extra partial courses, with an additional thread, separate from the main knitting thread, between the circular courses knit with the main knitting thread, which partial courses were each knit during the knitting of a circular course, certain of the 80 needles being operated twice in a single revolution of the machine. This process is efficient but necessitates an extra knitting cam and extra thread guide. Moreover, in knitting colored goods for the market it is 85 practically impossible to get two threads of the same color which are of exactly the same shade, and further no two threads are ever exactly alike in character and therefore do not take the dye alike. It is therefore extremely desirable that all the thread used in every portion of the stocking shall be off of the same bobbin if possible, as the use of different threads is very likely to produce mottled effects, in the finished fab- 90 ric.

My present invention has for its object the production of a tubular fabric having a segmental portion of less length than the other portions, and more specifically, a 100 stocking having the top portion of the foot of less length than the sole portion, by the simplest possible means with a single knitting thread, and so that no extra thread whatever need be used in the sole. To this 105 end I knit a tubular fabric (as for example the foot of a seamless stocking) with a single thread (by which term I mean one,

two, or more threads fed by a single thread guide at the same operation), which is fed circularly, that is to say, to each needle of the circular series consecutively and continuously, and I knit with said thread a plurality of circular courses, and a plurality of partial courses in a segment of the fabric, knit with the same thread intermediate adjacent circular courses, and prevent the formation of the remaining stitches of said partial courses, thus making the other segment, *i. e.*, the top of the foot of the stocking, shorter than the segment containing the partial courses, *i. e.*, the sole portion, by omitting partial courses from the top of the foot, and knitting the entire foot or tube with a single thread, instead of inserting extra courses in the sole formed of a separate thread, as in my former Patent No. 1,231,443.

The entire foot is thus formed of the same yarn and no variation in quality or color is likely to occur, and no additional thickening thread is required, although a splicing thread may be employed if it is desired. I prefer to carry my invention into effect by means of a circular knitting machine, and in the operation of such machine, when it is desired to form a partial course in one segment of the fabric and omitting the remaining portion of the course in the other segment of the fabric, the needles which knit the shorter segment are elevated out of operative relation with their knitting cam before they receive the thread, so that the thread which is fed circularly will engage these needles below their latches, the remaining needles receiving the thread in their hooks and forming stitches in the usual manner, while the elevated needles do not knit, and thus omit the balance of the course. Before the next course is knit, the elevated needles are drawn down into operative relation with the knitting cam and receive the thread for the next course of stitches within their hooks, above the latches so that when these needles are drawn down to knit the stitches of the next course (which will be a circular course) the thread previously fed below the latches in the preceding course will pass up over the latches as they close, and over the tops of the needles, to the interior of the tube where it will extend across the tube as a float from one end of the partial course to the other. In this manner a partial course is knit between adjacent complete circular courses and the remaining stitches of the partial courses are omitted, so as to shorten the fabric in which they would otherwise occur. These partial courses may be formed wherever desired and in any desired number through the circular knit fabric, as the foot of the stocking, and after the completion of the fabric, the float threads are cut out.

I may accomplish this result in other ways within the scope of my invention, as for ex-

ample, by depressing the needles knitting the part of the fabric which is not to be lengthened so that the thread will not be delivered to them at all, or by raising the needles knitting the lengthened fabric together with their operating cam and thread guide for the same purpose, or by causing the needles knitting the part of the fabric which is not lengthened to draw stitches and immediately cast them off. I prefer, however, to employ the means hereinafter described, and to prevent the formation of stitches in partial courses, by elevating the needles, and causing them to thereafter throw the thread, as before described.

In the accompanying drawings,

Figure 1 represents a side elevation of a stocking (a man's half hose) showing my invention embodied therein.

Fig. 2 is a diagrammatic view illustrating the circular series of needles, and the manner of feeding the single knitting thread thereto.

Fig. 3 is a diagrammatic view illustrating the relative positions of a needle knitting the longer portion and one knitting the shorter portion of the fabric, when receiving the knitting thread.

Fig. 4 is a diagrammatic view of the foot portion of a stocking embodying my invention, made by the herein described process of knitting in which a different distribution of the partial courses is indicated.

In Fig. 2 of the drawing I have indicated diagrammatically the circular series of instrumentalities (needles) upon which the tubular fabric, and particularly the seamless stocking illustrated diagrammatically in Fig. 1, is knit. In Fig. 2 1 represents the section of consecutive needles on which the shorter segment of the fabric is to be knit, and 2 represents the needles which knit the longer segment of the fabric, the dotted line $x-x$ indicating the line of demarcation between the two sets of needles. It will be understood, that the needles 1 and 2 are operated by a suitable knitting cam or cams, and the thread is supplied preferably to all of the needles by a single thread guide.

In carrying out my invention I supply during each circular course of knitting, a single thread (by which I mean a thread or two or more threads fed as a single thread) indicated at 3 to all of the needles 1 and 2, each of which is actuated to form a stitch, thus producing the ordinary circular course of stitches. When it is desired to make the segment knit by needles 1 of less length than that knit by needles 2, as in knitting the foot of a stocking, the thread indicated at 3^a in Figs. 2 and 3, is fed circularly to all of the needles as before, but each of the needles 1 is elevated (as shown in Fig. 3) out of operative relation with the knitting cam, and to such a position that the thread will be fed below the latch, while the thread is fed

in the usual manner to needles 2. It follows therefore, that while the needles 2 will each knit a stitch and form a partial course through a segment of the tube (as the sole of the foot of a stocking), the needles 1 will not knit and the remaining stitches of the partial course will be omitted from the other segment of the tube (as the top of the foot). On the completion of this course, the needles 10 5 will be drawn down into operative relation with the knitting cam and will receive the thread for the next course in their hooks, and as they draw the stitches for the next course, which will be a complete circular 15 course, the thread for the preceding course, which lies below their latches, will pass up over the closed latches and over the tops of the needles to the interior of the tube, and will extend across the tube from one end of 20 the partial course to the other as a float, indicated at 3^b, which afterward is cut out, as indicated by the dotted lines 3^c. As the length of the sole is what determines the standard size of the stocking, the sole is knit 25 with the desired or usual number of courses, complete and partial, the number of partial courses depending on the number of partial courses to be omitted from the top of the foot, and being preferably a sufficient number 30 to make the fabric of the top of the foot, a size or a half size shorter than the sole portion of the foot.

It is within the scope of my invention to omit the partial courses from the top of the foot by other means than by raising the needles 1. For example, they may be depressed so that the thread passes over them, or the needles 2 with their cam and their thread guide may be manipulated so 40 as to supply the thread to the needles 2, without supplying it to the needles 1, the essential feature being that a partial course which would ordinarily be knit on the needles 1, is suppressed or omitted, and the 45 thread floated, a partial course being knit on the needles 2 only.

In Fig. 1 I have shown a stocking knit by my improved process and embodying my invention. In this figure A represents the 50 usual ribbed top of a man's hose, B represents the leg portion, D the heel pocket, E the toe pocket joined to the top portion of the foot by the usual toe joining indicated at e. F represents the portion of the leg 55 above the heel which may or may not be reinforced as desired, C represents the top portion of the foot, and C' the sole portion of the foot.

In knitting the stocking shown in Fig. 1, 60 the ribbed top A is formed in the usual manner and "run on" or transferred to the needles of a circular knitting machine. The thread is then fed circularly to all the 65 needles 1 and 2, and the needles are operated to knit circular courses of stitches

forming the leg B, down to the beginning of the heel, as indicated by dotted lines 6—7—8. The heel D is then knit by reciprocating work and narrowing and widening on the group of needles 2, (the needles 1 remaining stationary and holding their stitches as usual), and preferably using a separate heel thread heavier than the main knitting thread, or in any other desired manner. In knitting the foot C—C', circular knitting is resumed with the knitting thread. In order to make the top of the foot shorter than the sole portion, I knit a certain number of partial courses 3^a in the sole, between adjacent circular courses 3, and 70 with the same knitting thread (or threads) and omit the corresponding partial courses from the top of the foot, in the manner heretofore described. I may knit these partial courses at intervals throughout the sole, 75 or I may introduce a number of them after each one of successive circular courses at one point only in the sole or at two or more points, as preferred. For example, I may knit a considerable number of them in the 80 part C³ of the sole adjacent to the heel, or I may locate a considerable number in the part C² of the sole adjacent to the toe, or I may locate part of them at each end of the sole, as at C²—C³, or at other points 85 in the sole, or I may distribute them singly or in small groups along the sole, as indicated at C⁴, in any case omitting a certain number of partial courses in the top portion of the foot, and knitting the complete 90 courses and the partial courses of the sole with the same thread. The resulting fabric will be a stocking in which the top portion of the foot will be from a half size to a size or more shorter than the sole, or 95 in other words, in which the sole will be longer than the top of the foot, thus when the stocking is worn, the sole which is of the proper length for the particular size stocking, will fit the sole of the foot, while 100 the top of the foot and instep portions being shorter will fit neatly and smoothly without forming the objectionable wrinkles noticeable in ordinary seamless stockings, and which look badly when worn with low 105 shoes, and which are a positive annoyance in causing undue pressure on the foot, whether worn with high or low shoes.

After knitting the sole, the toe pocket is 110 knit in the usual or any preferred manner, and the stocking is completed by looping the upper edge of the toe pocket to the edge 115 of the top portion of the foot, as at e, in the usual manner.

My invention may be carried out in many 120 ways, by hand, and also by mechanical means.

I have found it convenient to carry the 125 invention into effect by means of apparatus set forth in Letters Patent of the United 130

States granted to me, to wit, No. 1,347,186, patented July 20, 1920, and No. 1,368,664, patented February 15, 1921.

It is obvious that I may knit two or more consecutive partial courses in a segment of the tubular fabric, and suppress or omit a corresponding number of partial courses in the other portion of the fabric, if this is deemed desirable, but it will generally be preferred in practice to knit the partial courses single between adjacent or consecutive circular courses, as hereinbefore described.

In Fig. 4 I have shown diagrammatically the foot portion of a stocking embodying my invention, and made by the herein-described process of knitting in which a different distribution of the partial courses from that shown in Fig. 1 is indicated. In this figure A' represents the ribbed top, B' the leg, C' the top segment of the foot, C^o the bottom segment or sole portion of the foot, D' the heel, E' the toe, e' the toe joining, and F' the high spliced portion above the heel. In this diagram I have indicated the three successive complete courses of stitches at 3^b, and the alternating partial course intervening at every fourth course, at 3^c, it being understood that the foot of the stocking may be knit throughout with an extra partial course after every third complete circular course throughout its length, or that this course may be pursued through a portion or portions of the foot of the stocking as may be desired. I have also indicated in this figure a toe band, indicated at c^o which I preferably knit of circular courses only, adjacent to the toe pocket, although this is not essential.

In carrying out my invention the thread is fed circularly in the same direction at all times during the knitting of circular knit tubular work. In knitting a stocking according to my invention, the invention is applied usually to the circular knit tubular foot portion between the heel pocket and toe pocket, but the invention is applicable to any circular knit tubular fabric. It is to be clearly understood that where I have referred to circular courses and the feeding of the thread circularly herein, I always mean to refer to circular knitting, in which the thread is fed continuously in the same direction, and distinguished from reciprocating knitting which is always termed reciprocating knitting whether the thread is fed all or a part of the way around the tube.

What I claim and desire to secure by Letters Patent is: —

1. The herein described process of knitting a circular knit tubular fabric, which consists in feeding a continuous main knitting thread circularly and continuously in the same direction, and forming a plurality

of circular courses of stitches and preventing the formation of stitches through portions of single courses located in the same segment of the fabric, to produce single partial courses of stitches in the other segment of the fabric between adjacent circular courses knit with the same thread, all the stitches of the circular and partial courses being of substantially the same size. 65

2. The herein described process of knitting a circular knit tubular fabric, which consists in feeding a continuous main knitting thread circularly and continuously in the same direction throughout the formation of said circular knit fabric, knitting a plurality of complete circular courses of stitches, and preventing the formation of stitches through portions of single courses located in the same segment of the fabric to produce single partial courses of stitches in the other segment of the fabric, between adjacent circular courses, knit with the same thread, and floating the thread from one end of each partial course across the tube, all the stitches of said circular and partial courses being of substantially the same size. 75 80 85 90

3. The herein described process of knitting a tubular fabric having a segmental portion of less length than other portions of the tubular fabric, which consists in feeding a single knitting thread circularly and forming a circular course of stitches, then feeding the same thread circularly in the same direction and knitting a partial course of stitches upon a group of stitches of said circular course, and carrying the thread across the tubular fabric, and then feeding the same thread circularly in the same direction and knitting a circular course of stitches upon said partial course of stitches, and the remaining stitches of the preceding circular course not connected with the stitches of said partial course. 95 100 105

4. The herein described process of knitting a tubular fabric having a segmental portion of less length than the remaining portion of such tubular fabric, which consists in feeding a single knitting thread circularly to a circularly arranged series of instrumentalities, and operating all of said instrumentalities to form a circular course of stitches, feeding the same thread circularly in the same direction to all of said instrumentalities, and causing a portion of consecutive instrumentalities to throw off the said thread, feeding the same thread circularly in the same direction and operating all of said instrumentalities to form a circular course of stitches upon the partial course, and the portion of the preceding circular course not connected therewith. 110 115 120 125

5. The herein described process of knitting a tubular fabric having a segmental portion of less length than the remaining

portion of such tubular fabric, which consists in feeding a single knitting thread circularly to a circularly arranged series of instrumentalities, and operating all of said instrumentalities to form a circular course of stitches, feeding the same thread circularly in the same direction to all of said instrumentalities, operating all of said instrumentalities, and placing a segmental portion of 5 said instrumentalities in inoperative position at the time the thread is fed to them, whereby a partial course of stitches will be formed, restoring said inoperatively positioned instrumentalities to operative position 10 and feeding the same thread circularly in the same direction to form a circular course of stitches upon the stitches of the partial courses and the stitches of the portion of the preceding circular course not engaged 15 by the stitches of the partial course. 20

6. The herein described process of knitting a tubular fabric having a segmental portion of less length than the remaining portion of such tubular fabric, which consists in feeding a single knitting thread circularly to all of a circularly arranged series of instrumentalities and operating all of 25 said instrumentalities to form a circular course of stitches, feeding the same thread 30 circularly in the same direction to all of said instrumentalities, placing a segmental portion of said instrumentalities in inoperative position at the time the thread is fed to them, and causing them to hold the stitches 35 of the preceding circular course without knitting, whereby a partial course of stitches will be formed, then feeding the same knitting thread circularly in the same direction to all of the series of instrumentalities while 40 in operative position, and knitting a complete circular course of stitches upon the stitches of the said partial course and upon the stitches of the said preceding circular course not connected with the partial course, 45 and causing the needles which were moved to inoperative position during the knitting of the partial course to cast off during the knitting of said circular course the knitting

thread fed to them while they were in inoperative position. 50

7. The herein described process of knitting a seamless tubular stocking which consists in knitting the leg by circular knitting, forming the heel pocket, knitting the foot portion by continuous circular knitting with 55 a single thread, fed continuously in the same direction, and forming circular courses, forming partial courses in the sole portion of the foot with the same thread, between circular courses, and omitting the remaining stitches of such partial courses over the top of the foot, and floating the said thread from one end of each of said partial courses across the tube. 60

8. The herein described circular knit tubular fabric comprising a plurality of complete circular course of stitches of substantially the same size throughout and knit with the same thread, and single partial courses of stitches of substantially the same 70 size as those of the circular courses located between adjacent circular courses and formed of the same thread as that composing the circular courses, said partial courses being located in the same segment of the 75 tubular fabric. 85

9. A fashioned seamless stocking having the foot portion between the heel and toe pockets composed of circular knitting throughout, and comprising a plurality of circular courses of stitches of substantially the same size and formed from the same thread, and single partial courses of stitches formed from the same thread lying between adjacent circular courses, and located in 80 the sole portion of the foot and being of substantially the same size as the stitches of the circular courses, whereby the top portion of the foot is made shorter than the corresponding sole portion, the entire foot portion between the heel and toe pockets being 85 a uniform fabric, and knit with the same thread. 90

In testimony whereof I affix my signature.

WILLIAM E. SMITH.
